(57) **CLAIM**

The ornamental design for an aircraft galley, as shown and described.

DESCRIPTION

FIG. 1 is a front view of an aircraft galley showing our new design in an aircraft cabin;

FIG. 2 is a forward perspective view of the aircraft galley of FIG. 1;

FIG. 3 is an aft perspective view of the aircraft galley of FIG. 1;

FIG. 4 is a right side view of the aircraft galley of FIG. 1; and,

FIG. 5 is a left side view of the aircraft galley of FIG. 1. In the drawings, the dash-dash broken lines depict unclaimed environmental subject matter only and form no part of the claimed design. In FIGS. 1, 2, and 3, the dot-dash-dot broken lines depict boundaries of the claimed design, and form no part of the claimed design.

1 Claim, 5 Drawing Sheets

FIG. 1

FIG. 2

FIG. 3

FIG. 4

FIG. 5
